United States Patent Office

Des. 221,835

Patented Sept. 14, 1971

221,835

COMBINED BOTTLE AND CLOSURE THEREFOR

Cyril Edward Higgs, Leeds, England, assignor to Lever Brothers Company, New York, N.Y.

Filed Apr. 13, 1970, Ser. No. 22,398

Claims priority, application Great Britain Oct. 15, 1969

Term of patent 14 years

Int. Cl. D9—01

U.S. Cl. D9—149

Fig. 1.

Fig. 2.

Fig. 3.

Fig. 4.

FIG. 1 is an elevational view of a combined bottle and closure therefor showing my new design;

FIG. 2 is an elevational view looking from the right of FIG. 1;

FIG. 3 is a top plan view; and

FIG. 4 is a bottom plan view thereof.

I claim:

The ornamental design for a combined bottle and closure therefor, substantially as shown.
